GAS DISCHARGE DEVICE AND CIRCUIT
THEREFOR

Samuel Ruben, New Rochelle, N. Y.

Application July 5, 1940, Serial No. 344,031

2 Claims. (Cl. 176—124)

This invention relates to a gas discharge device and specifically to an electric lamp of the fluorescent type capable of directly starting and operating on a 120 volt alternating current line without the use of electro-mechanical control devices. This application is a continuation in part of my co-pending application bearing Serial Number 332,469, filed April 30, 1940.

The general object of the invention is the provision of a gas discharge lamp of simple structure, which can be economically manufactured, and which in combination with the circuit to be described, operates on low commercial alternating current lines without an auxiliary starting device.

Other objects will be apparent as the disclosure proceeds and from the drawing which shows a fluorescent tube and circuit embodying the invention.

In this invention I utilize a lamp structure of the type described in my prior and co-pending application above referred to, the lamp preferably being in tubular form and having end electrode assemblies, each comprising an oxide coated electron emitting filament and a cooperating electrode which may be in rod form, the discharge between the electrodes of each assembly, heating the oxide coated filaments to thermionic emission temperature.

In the prior art, where cold starting means have been applied, as for example, by use of a step-up transformer, mechanical interruption of an inductance, etc., the voltage necessary to discharge through the entire tube length has been such as to cause (by ionic bombardment) rapid destruction of the electrode elements. In the present invention, due to close spacing between the electrodes effecting the ignition discharge, this destructive factor is limited.

In my new arrangement, ionic discharge assemblies each consisting of a thermionic emission element, preferably in filament form, and a cooperating element, preferably in rod form, are mounted at each end of the tube. An inductance is connected in series with a condenser to provide the ignition voltage for one pair of electrodes, the voltage being obtained across the inductance. Ignition voltage for the other pair of electrodes is obtained across this condenser, and the current discharge is limited by a condenser or other impedance in series with these electrodes. The ionic discharge between the rod and filament electrodes heats the filament to electron emission temperature. The electron emissivity of the filament when hot, plus the

ionized atmosphere in the electrode discharge area, allow a ready discharge of the line voltage through the tube without raising the voltage applied to the tube for effecting the discharge, the line current discharged through the tube being limited by an inductance.

While the method and apparatus described are particularly suited to the fluorescent type of tubes, they can be used with other types of gas discharge tubes.

In order to further describe the invention, reference is made to the accompanying drawing in which is shown an enclosed glass tube 1, of 15 watt size, coated with a fluorescent material, such as silicate of zinc, cadmium, beryllium or other combinations known to the art. At one end of the tube is rod electrode 2 which extends through low mass coiled filament 3, formed of 2 mil tungsten wire coiled to a length of 2½ inches with 200 turns to the inch, then coated with a mixture of strontium and barium oxides in the manner well known to the art. At the opposite end of the tube is a similar electrode assembly, the rod 5 being similar to rod 2 and filament 6 being similar to filament 3. Insulator tube 4 of Isolantite or similar material covers part of rod 2 so as to confine the discharge between electrodes 2 and 3 to the end of the assembly and provide rapid direct heating of the electron emitting coiled filament. Insulator tube 7 performs a similar function in respect to rod 5 and filament 6.

Condenser 8 of ¾ mfd. capacity is connected across ¼ mfd. condenser 9, which is in series with rod and filament 5 and 6. As the voltage is developed across condenser 9 connected across alternating current line 12 in series with 5700 ohm impedance 11, the connection of capacitance 8, allows the same ignition voltage to be applied to the electrodes 2 and 3 as is applied to the electrodes 5 and 6 due to their connection across impedance 11. The reactances of impedance 11 and capacitance 9 are such that voltages sufficient to start the discharge between the rod and filament electrodes are obtained. Capacitance 8, which serves to apply the voltage developed across capacitance 9 to the rod and filament assemblies can be replaced by other current-limiting means such as a resistance of about 1500 ohms or an inductance impedance where efficiency is not the major factor. Inductance 10, having an impedance of 300 ohms at 0.3 ampere, connected in series with filament 3 and the line, serves to limit the current discharged through the length of the tube. A ca-

pacitor can be interposed between inductance 10 and the line to obtain power factor correction of the circuit.

After the electrodes have been mounted, the tube is completely evacuated and degasified and is then filled with a gas of low ionization potential at about 5 millimeters pressure, such as argon or neon or a mixture of 70% argon, 30% neon. A small amount of mercury is also added to increase the ultra-violet component of the discharge and thus increase the radiation activation of the fluorescent coating on the wall of the tube.

In operation, when voltage is applied, there is an ionic discharge between the rod and filament electrodes at the ends of the tube which ionizes the end areas. The filament becoming heated, allows a low voltage to be maintained between these electrodes, and due to the effect of the heated filaments and the ionized discharge between the electrodes of each end assembly, a discharge takes place throughout the length of the tube, the voltage dropping to approximately 60 volts. After starting, the capacitances 8 and 9 serve to limit the current applied to the end electrode assemblies. Condenser 9 also serves the added function of allowing the voltage across inductance 11 to reach a value greater than the line voltage or approach a resonant condition thereby providing ignition voltages across the opposite pairs of electrodes. Thus, by varying the ratio of the inductance 11 to the capacitance 9, voltage greater than the line voltage can be applied to the electrodes, thereby avoiding the necessity of critical spacing or critical gas pressure. The electrical characteristics of the end assembly determine the extent of resonance, if any, in the circuit and is dependent upon the electrode materials, gas pressure and spacing of electrodes, some combinations discharging at voltages below the line voltage.

The electron emitting electrodes of the tube should be of small mass and preferably of the alkaline oxides coated filament type so as to be capable of instantaneous heating to thermionic emission temperature. For a 15 watt lamp of 18

inch length and 1 inch diameter, a coiled 2 mil tungsten wire weighing 20 milligrams has been been found satisfactory. The size and weight of the filament will naturally be determined by the value of the applied current.

Having described my invention, what I claim as new and desire to secure by Letters Patent, is:

1. In combination with an electric gaseous discharge device comprising a sealed envelope, a gaseous atmosphere within said envelope, a pair of ionic discharge electrode assemblies at each end of said envelope each comprising a filamentary and cooperating electrode, the filament electrodes being connected to opposite terminals of an alternating current line with a current-limiting reactance in series; an auxiliary circuit connected to the line comprising an inductance and a series capacitance, one electrode assembly being connected to said inductance and the other electrode assembly connected to said capacitance, with current-limiting means to limit the discharge from said capacitance.

2. In combination, an electric gaseous discharge device comprising a sealed tube, a gaseous atmosphere within said tube, an ionic discharge couple at each end of the tube, each couple comprising a thermionic electron emitting filament and a cooperating electrode, an alternating current line, an inductance in shunt with the electrodes of one of said couples, the filament of said couple and one terminal of said inductance being connected to one side of said line, the other terminal of said inductance and the cooperating electrode of said couple being connected to a terminal of a capacitance, the other terminal of the capacitance being connected to the other side of said line, said other side of the line being connected to the filament of the other couple through an inductance in series therewith, the cooperating electrode of said other couple being connected to a terminal of a current-limiting means, the other terminal of which is connected to said capacitance and to the cooperating electrode of the other couple.

SAMUEL RUBEN.
